UNITED STATES PATENT OFFICE.

ERNEST FRANK, OF BALTIMORE, MARYLAND.

IMPROVEMENT IN ROTARY ENGINES.

Specification forming part of Letters P. tent No. 158,697, dated January 12, 1875; application filed March 6, 1874.

To all whom it may concern:

Be it known that I, ERNEST FRANK, of the city of Baltimore and State of Maryland, have invented certain improvements upon the patent granted to Samuel Gibson, August 12, 1873, for certain improvements in rotary engines, and numbered 141,710, of which improvements the following is a specification; and I do hereby declare that in the same is contained a full, clear, and exact description of my said invention, reference being had to the accompanying drawing and to the letters of reference marked thereon.

My invention relates to certain improvements in or upon the valve arrangement of the engine, as fully hereinafter set forth. The engine herein described and illustrated is reversible, and the devices and combination thereof constituting my invention are specially adapted to engines capable of a backward and forward movement. Other features not forming a part of my invention are herein set forth, the explanation thereof facilitating a correct understanding of the invention hereinafter specifically claimed.

In the further description of my invention which follows due reference must be had to the accompanying drawing, in which Figure 1 is a vertical section, Fig. 2 a central transverse section, and Fig. 3 an enlarged view, of a portion of the invention.

Similar letters of reference indicate similar parts in all the views.

A is the steam-cylinder. B and C are, respectively, the fixed and removable cylinder-heads. D is the steam-chest, fastened to a projecting face cast upon the cylinder, and within which is the reversing slide-valve α operated by means of a stem projecting through a wall of the chest. E E' are the steam-ports leading from the chest D to the interior of the cylinder. The location of the upper ends of the ports is such with relation to the lengths of the valve and chest that either can, by the movement of the valve α , be brought into communication with the interior of the cylinder. F F' are exhaust-ports leading from the cylinder to the space formed in the lower side of the reverse valve α . By means of this space one of the exhaust-ports is continually in communication with the outlet-pipe G. H is the cy-

lindrically-formed piston fastened to and supported by the main shaft b , which revolves in the bearings $c c'$ on the cylinder-heads. The center of the piston is elevated considerably above the center of the cylinder, the lines representing the periphery of the piston and the inner circumference of the cylinder being eccentric with each other, and coming in contact at the upper side. The piston is slotted for the reception of the valves I I', which fit therein as nearly steam-tight as is practicable. The valves are connected by the rod d , which rests at either end in sockets in the valves, the socket in valve I being sufficiently large to allow of the introduction of a collar formed on the rod. The valves I I' are not equidistant during an entire revolution of the piston, and this variation in distance prevents the rod being constructed so as to bear against both valves. To compensate for this irregularity, I place a spiral spring in valve I of such length and degree of tension as is necessary at all times to place the required strain upon the valves. The valves I I', although constructed alike as regards the steam-passages therein, when placed in their respective grooves and steam admitted to them through the ports E E', influence the piston in opposite directions. The valves are provided with two channels, $e e'$, running longitudinally of them, the one e extending entirely to the inner end of the valve, and that e' being closed at the inner end to prevent the admission of steam from the spaces f existing between the ends of the valves and the piston. Apertures g lead from the channels e' to steam-port E', but have no communication with the port E, steam issuing from the valves to the interior of the cylinder through the openings h . Access from the steam-port E to the valves is through the spaces f and channels e , and thence to the cylinder by means of the openings h . The adjustable faces before alluded to as added to the valves are represented by k and shown in Fig. 1. K is a bearing-piece inserted in a recess in the upper portion of the cylinder, adjusted by means of set-screws, to compensate for wear at its point of contact with the piston. L is the piston-follower, which is held stationary within the cylinder and bears against the face of the piston, forming a steam-tight joint. Leakage from the cylinder is pre-

vented by means of a gasket, *m*, of gum or other flexible material, fitted to a groove around the follower *L*. The movable parts of the engine being relatively placed as shown in the drawing, steam admitted to the steam-chest passes down the port *E* and into the space *f*, which is in direct communication through the channel *e* and opening *h*, with the interior of the cylinder above the valve, and the piston is caused to revolve in the direction of the arrow, the valve at the same time being forced against the cylinder, forming a steam-tight joint.

It will be understood that in an engine constructed as described the steam, although operating to force out the valve, is not depended upon solely for this office, as the rod *d* with the spiral spring will keep the valves in contact with the cylinder. Steam has no access to the cylinder until the outer edge of the opening *h* has passed beyond the periphery of the piston, and consequently, as the said opening again passes the circumference of the piston on the return of the valve toward the center of the piston, the steam is cut off and expansion takes place, continuing until the valve has passed the exhaust-passage *F'*.

The engine is reversed by moving the reverse-valve *a* and exposing the port *E'*, thus admitting steam to the upper face of the valve *I'*.

That portion of the port *E'* which is curved or circular is struck from such a center as will enable the said circular part of the port to be opposite, throughout its entire length, to a portion of the opening *g* in the valve *I'* during its revolution; and, in reversing the engine, the steam continues to flow into the port *E'* until the valve *I'* reaches the end thereof. It is, of course, understood that before the port *E'* can be used as a channel for steam in reversing the engine, the steam-port *E* must be closed, the valve *a* being moved so as to cover it and expose the port *E'*.

Having thus described my invention, what I claim as new, and desire to secure by Letters Patent of the United States, is—

The valves *I* *I'*, constructed with their respective ports, as described, and mounted upon a common rod, *d*, of variable length, in combination with the adjustable faces *k*, having arcs coincident with the interior of the cylinder, substantially as specified.

In testimony whereof I have hereunto subscribed my name in the city of Baltimore this 3d day of March, 1874.

ERNEST FRANK.
